UNITED STATES PATENT OFFICE.

FRANCIS DRAPER, OF BOSTON, MASSACHUSETTS.

HEEL-PLATE.

SPECIFICATION forming part of Letters Patent No. 269,269, dated December 19, 1882.

Application filed October 30, 1882. (No model.)

To all whom it may concern:

Be it known that I, FRANCIS DRAPER, of Boston, in the county of Suffolk and State of Massachusetts, have invented an Improvement in Heel-Plates for Boots and Shoes, of which the following is a full, clear, and exact description, reference being had to the accompanying drawings, making part of this specification, in which—

10 Figure 1 is a perspective view of a heel-plate constructed in accordance with my invention. Fig. 2 is an elevation of the same. Fig. 3 is a plan of the under side of a heel with my improved heel-plate applied thereto. Fig. 4 is a vertical section on the line *x x* of Fig. 3.

15 My present invention relates to that class of heel-plates for boots and shoes cut or punched from a flat piece of metal, and provided with prongs at right angles thereto, this invention 20 having special reference to that described and shown in Patent No. 148,392. The heel-plate constructed in accordance with said patent has a straight side provided with a series of shanks or prongs "arranged in a line parallel 25 to and flush with the edge of the straight side," which construction is objectionable for the following reasons: After continued use the prongs become disconnected from the metal of the flat portion of the plate at points immediately under and in line with the prongs, there being nothing to protect the bottoms of the prongs from contact with the ground, after which the flat body of the plate, having nothing to retain it in place, drops off from the heel 30 of the boot or shoe to which it was applied, and as a heel should outwear several plates a difficulty arises in removing the old detached prongs of one plate to allow of the introduction of the prongs of a new plate. Again, the said 35 heel-plate described in Patent No. 148,392 cannot be readily applied, owing to its liability of tipping to one side when struck by the hammer; and, furthermore, as said plate is let into the heel flush with its bottom, by removing a 40 portion of the lifts corresponding in size and depth with that of the plate, the heads of the nails, ordinarily located at this point, have either to be driven in or cut off to enable this to be done.

45 50 To remove the above-mentioned objections is the purpose of my present invention, which consists in a metal plate having one side curved

to conform to the curvature of the outer edge of the heel, and its other side of irregular form, provided with a series of prongs at right angles to the body of the plate for entering the heel, and a series of projections on each side of the prongs and located in the same plane as the flat body of the plate, in order to balance the same and afford suitable surfaces for the hammer to strike against when the prongs are being driven into the heel, whereby the plate is brought evenly upon and made to fit snugly the bottom of the heel, the dropping off of the flat portion of the plate, after being separated from the prongs, occasioned by the constant wear at the bottoms of the prongs, as well as the crippling or bending of the same, and the cutting of the heel incident to heel-plates not provided with said projections, being entirely avoided.

To enable others skilled in the art to understand and use my invention, I will proceed to describe the manner in which I have carried it out.

75 In the said drawings, A represents a heel-plate cut or punched out of a flat piece of metal, said plate having a curved side, *a*, corresponding to the curvature of that portion of the heel which wears unevenly, and its other side, *b*, of irregular form, and provided with a series of curved projections, *c*, and a series of pointed prongs, *d*, each prong being located between two contiguous projections, and being struck or bent up at right angles to the flat body of 80 the plate, the prongs being arranged out of line with each other, and the bottom *e* of each, where it projects up from the flat portion, being so bent as to occupy a position in a horizontal plane above that passing through said 85 flat portion, the said projections affording convenient surfaces for receiving the blows of the hammer when the prongs are being forced into the holes prepared for them in the bottom 90 of the heel by means of an awl.

95 100 The location of the projections on each side of the prongs serves to guard the bottoms of the latter and protects them from being worn so rapidly as would be the case were the prongs turned down on a line with the straight side of the plate, as set forth in the patent herein referred to, the prongs in a plate constructed in accordance with my invention lasting as long as and remaining integral with the plate

till the latter is worn out. By means of the projections I am enabled to seat the flat portion of the plate squarely on the outside of the bottom of the heel, no tipping of the plate or 5 crippling of the prongs occurring, and no cutting away of a portion of the heel or cutting off or driving in of nails to properly apply the plate being necessary.

I claim—

- 10 As an improvement in stationary heel-plates, a flat sectional heel-protector, A, of metal, having a curved side, *a*, corresponding to the curvature of the outer edge of the heel to which it is to be applied, and an irregular side, *b*, 15 formed by a series of prongs, *d*, at right angles to the flat surface of the plate, and a series of

projections, *c*, lying in the same plane with and extending from the said flat surface beyond the prongs, and located on each side thereof, in order to constitute guards therefor, whereby 20 they are protected from being unduly worn and separated from the flat portion of the plate at their points of intersection therewith, the construction and arrangement of the several parts being as described, for the purpose set 25 forth.

Witness my hand this 14th day of October, 1882.

FRANCIS DRAPER.

In presence of—

JAS. W. CHAPMAN,
N. W. STEARNS.
